The ornamental design for a flashlight caddy, as shown and described.

DESCRIPTION

FIG. 1 is a perspective view of the flashlight caddy showing my new design;

FIG. 2 is a front view of the flashlight caddy;

FIG. 3 is a back view of the flashlight caddy;

FIG. 4 is a top view of the flashlight caddy;

FIG. 5 is a bottom view of the flashlight caddy;

FIG. 6 is a side view of the flashlight caddy, where the right side view and the left side view are mirror images of each other; and,

FIG. 7 is a front view of the flashlight caddy with the flashlight caddy shown in an open position.

The strap and flashlight shown in large broken lines are for environmental purposes only and form no part of the claimed design. The smaller dashed lines along the inner perimeter of the flashlight caddy are stitching and do form part of the claimed design.
